CLAIM

The ornamental design for a tool pouch with a holster for a cordless drill, as shown and described.

DESCRIPTION

FIG. 1 is a perspective view of a tool pouch with holster for a cordless drill, showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken line showing of a drill in FIG. 1 is for illustrative purposes only and forms no part of the claimed design.

FIG.1.

FIG.3.

FIG.2.

FIG.4.

FIG. 5.

FIG. 6.
